UNITED STATES PATENT OFFICE.

ELI N. BALDWIN, JR., OF STRATFORD, CONNECTICUT.

CONCEALED HINGE.

1,073,316.

Specification of Letters Patent.

Patented Sept. 16, 1913.

Application filed August 12, 1912. Serial No. 714,551.

To all whom it may concern:

Be it known that I, ELI N. BALDWIN, Jr., a citizen of the United States, residing at Stratford, county of Fairfield, State of Connecticut, have invented an Improvement in Concealed Hinges, of which the following is a specification.

This invention has for its object to provide an inexpensive but very strong and rigid concealed hinge adapted for general use and especially adapted for use as an automobile or coach hinge, so-called, the hinge being wholly concealed in the closed position, being flush with the surface of the jamb in the open position and being so constructed as to positively retain the door out of contact with an automobile or coach body when in the open position.

With these and other objects in view I have devised the novel concealed hinge which I will now describe, referring to the accompanying drawing forming a part of this specification and using reference characters to indicate the several parts.

Figure 1 is a horizontal section of a door and jamb, my novel hinge appearing in plan, the door being shown in full lines in the closed position and in dotted lines in a partly open position; Fig. 2 a similar view, the door being in the fully open position and the hinge members in section on the line 2—2 in Fig. 3, looking in the direction of the arrows; Fig. 3 a view of the face of the jamb and the inner face of the door showing the hinge in the fully open position; Figs. 4 and 5 perspectives of the hinge members detached, and Fig. 6 is a view similar to Fig. 2, showing a slight modification in the hinge members to permit the door to be swung past an angle of 90 degrees in the open position.

10 denotes the door member of the hinge as a whole, 15 the jamb member, 20 a door and 21 a jamb. The jamb member comprises a stop plate 22 which for convenience I will describe as lying in the vertical plane, attaching flanges 23 which lie in a vertical plane at right angles to the plane of the stop plate, and side plates 24 which lie in the horizontal plane and connect the attaching flanges to the stop plate. The door member comprises an attaching plate 25 and an angle plate comprising arms 26 and 27, arm 26 extending at a right angle from the attaching plate and outer arm 27 extending inward at a right angle to arm 26 and par-

allel with the attaching plate. The inner ends of stop plate 22 and of arm 27 of the angle plate are provided with corresponding hinge eyes 28 through which a pin 29 passes, 60 in the usual manner.

In attaching my novel hinge in place the jamb member is let into an opening in the face of the jamb and attaching flanges 23 are also let into the face of the jamb, so as 65 to lie flush therewith. Attaching plate 25 of the door member is likewise let into the edge of the door so as to lie flush therewith.

The operation will be readily understood from the drawing. In the closed position 70 the recess in the jamb receives the whole of the door member with the exception of the attaching plate, the arms of the angle plate swinging freely between side plates 24. The closed position of the members will be readily understood from Fig. 1. It will be noted furthermore from Fig. 1 that owing to the 75 arc of movement of the angle plate, the recess in the jamb only requires to be made just large enough to contain the angle plate 80 in the closed position, as in the opening movement arm 27 swings away from the wall of the recess (see dotted position in Fig. 1). When the door is swung to the fully open position, arm 27 of the angle plate will lie 85 flat against the surface of stop plate 22, as clearly shown in Fig. 2. This engagement of plate 27 with the stop plate limits the opening movement of the door and renders it impossible for the edge of the door to 90 strike the highly finished surface of an automobile or coach body.

Ordinarily it is preferred that the door swing to an angle of about 90 degrees to the plane of the body. If preferred, however, by bending arm 26 to a more or less acute angle to arm 27 instead of to a right angle thereto, and slightly cutting away the edge of stop plate 22, the door may be swung past an angle of 90 degrees, 100 as clearly shown in Fig. 6.

Having thus described my invention I claim:

1. A concealed hinge formed from sheet metal and consisting of a jamb member 105 comprising a stop plate in the vertical plane, attaching flanges in the vertical plane and at right angles to the stop plate and side plates in the horizontal plane which connect the attaching flanges to the stop plate, and a door member comprising an attaching plate and an angle plate one arm 110

of which is connected to the attaching plate, the other arm extending at a right angle and parallel with the attaching plate, said stop plate and second mentioned arm being 5 provided with hinge eyes.

2. A concealed hinge formed from sheet metal and consisting of a jamb member comprising a stop plate and side plates at an angle thereto, said stop plate being provided 10 with hinge eyes and said side plates with attaching flanges, and a door member com-

prising an attaching plate and an angle plate having an arm lying parallel with the attaching plate and provided with hinge eyes.

In testimony whereof I affix my signature in presence of two witnesses.

ELI N. BALDWIN, JR.
